SAFETY RAZOR

Carlyle B. Stair, Downers Grove, Ill.

Application November 19, 1934, Serial No. 753,666

5 Claims. (Cl. 185—37)

This invention relates to improvements in safety razors.

As well known to users of safety razors, in order to prevent rusting of the thin blades and thereby prolong their usefulness, it is essential not only to remove the usual residue of shaving soap or cream remaining on the blade and associated parts after use but also to thoroughly dry the blade after each use. Failure to do this causes quick oxidation or rusting of the usual thin steel blade, particularly along the cutting edges, so that they cannot thereafter be re-used. Heretofore, so far as known, the common practice to effect the necessary drying of the blades after use, has been to first rinse the razor parts either while in normally assembled condition, loosely assembled, or individually while entirely separate and then, with the blade entirely separate from the other parts of the razor, wipe the blade dry with a cloth or towel. Not only does this procedure involve an appreciable amount of time, generally when the user has only a limited time available, but frequently results in cutting of the user's fingers or the towels, or both, and, if the drying of the blade is not done promptly and regularly after each use of the razor, a certain amount of rust will form on the blade, which is transferred to the towel, all to the general irritation and annoyance of the razor user and owner of the towels.

One object of this invention is to provide an improved safety razor having incorporated therein simple, efficient and inexpensive means for effectively, thoroughly, and substantially instantaneously drying the working parts of the razor, and particularly the usual wafer blade, after a use and rinsing thereof, all without disassembling the parts or detaching the blade and without the use of any extraneous devices or apparatus.

Another object of the invention is to provide means of the character indicated in the preceding paragraph which will accomplish the desired results by a rapid air-drying of the parts while the razor is held in the user's hand and, more specifically, by imparting a rapid rotation to the blade and/or associated usual support and clamp, the drying being thus effected in part by a centrifugal action to throw off the moisture and, in part, by rapid movement of the blade surfaces through the air.

In the use of certain so-called brushless shaving creams, difficulty is experienced in removing the usual residue by the ordinary rinsing methods either under the stream from a faucet or by

agitation in a bowl of water, and a further object of the present invention is to utilize the novel means primarily intended for the drying of the razor parts, for facilitating the quick removal of such cream residues that are otherwise difficult to remove by ordinary methods.

A more specific object of the invention is to provide means for accomplishing the results indicated in the preceding paragraph such that said means may be readily incorporated in most of the commercial types of safety razors now on the market without necessitating any change in the distinctive or characteristic features thereof employed in the mounting and retaining of the blades.

Other objects of the invention will more clearly appear from the description and claims hereinafter following.

In the drawing forming a part of this specification, Figure 1 is a side elevational view of a safety razor showing the improvements incorporated therein, the particular safety razor chosen for illustration being of a well-known commercial type as regards the blade, support and clamping arrangement. Figure 2 is a view similar to Figure 1 with parts of the handle structure shown in longitudinal section and with the blade and clamp loosened or adjusted to separate the edge portions of the blade from the clamp. Figure 3 is a view similar to Figure 1 with the blade assembly proper omitted and illustrating the condition of the elements of the handle means after the spring has been released. Figure 4 is a transverse sectional view corresponding substantially to the line 4—4 of Figure 2. Figure 5 is a broken detail perspective view of the inner end of the handle member proper. And Figure 6 is a view similar to Figure 2 of the blade assembly only and illustrating another way in which the blade may be loosened and positioned preparatory to the whirling motion to be imparted thereto for drying and/or cleansing.

In said drawing, the razor is shown as comprising a combined blade-support and guard A; a wafer blade B; a clamp and blade-tensioning member C; a spindle D; a handle member proper E; a spring F; and a plunger G.

The combined support and guard A is of well-known form having a flat supporting surface proper 10 and a series of laterally spaced curved guard fingers 11—11 along each longitudinal edge thereof, the supporting surface having a longitudinally extending groove 12 with which cooperates a corresponding longitudinally extending rib 13 formed integrally with the curved

clamping member C. In the type of safety razor shown, the rectangular wafer blade B is centrally slotted to receive therethrough the rib 13 and the blade is flexed to the desired curvature over the rounded edges 14 of the support when the clamp is pulled up tightly by the well known threaded stem 15 of the clamping member which is extended through the blade and also through the support A, where it is engaged by the inferiorly threaded or nut formation 16 on the inner end of the spindle member D. In Figure 1, the razor parts proper are shown in condition for shaving, wherein the blade B is curved and tightly clamped and the operating nut and threaded parts screwed together tightly. In the particular type of razor shown, the curved clamp C is provided with four corner bosses 17 which are accommodated through the four notched corners of the blade as best indicated in Figure 1 so that the active cutting edges 18 will normally bear against the longitudinally flat edges 19 of the clamp between each pair of bosses 17 on each side thereof.

In carrying out the present invention, the spindle member D which is employed to detachably lock the support A, blade B and clamp C, is formed at its inner end with a cylindrical bearing 20. Said bearing is provided at its outer end with a pair of diametrically disposed inclined slots 21 each with a relatively large flaring mouth adapted to facilitate admission thereto and release therefrom, of the hook shaped inner end 22 of the spring F, for the purpose hereinafter described. The bearing section 20 is also provided with a radially extended pin 23 constituting part of a ratchet mechanism for a purpose hereinafter described, said pin being located preferably closely adjacent a knurled section 24 formed on the spindle element.

The plunger G, which is extended entirely through the handle member E, may be formed integrally with the spindle element D, but, preferably for manufacturing purposes, is separately formed and driven endwise with a wedge friction fit at its inner end into a corresponding recess on the bearing section 20 of the spindle. At its outer end the plunger G is of slightly enlarged diameter, as indicated at 25, the same forming another bearing for the outer end of the handle E, and the main portion of the plunger providing an arbor like support for the spring F, as clear from Figure 2.

The handle member E proper is preferably in the form of a hollow cylindrical tube suitably knurled on its outer surface, as indicated at 26, and having an enlarged solid section 27 at its outer end, the latter preferably being separately formed and provided with a reduced diameter bushing 28 which is driven with a wedge friction fit within the outer end of the handle member E proper as shown in Figure 2. With the construction described, it will be seen that the handle member E is rotatably mounted with respect to the spindle and plunger G at both ends of the handle member and, furthermore, is adapted for longitudinal movement with reference thereto for a limited extent which is governed by the collar 29 at the outer end of the plunger, which collar, when the plunger is operated as hereinafter described, is adapted to be pushed within a corresponding annular recess 30 provided in the outer handle section 27, as shown in Figure 3. The inner end of the handle member E is provided with preferably two diametrically disposed bayonet notches or recesses 31—31 constituting with pin

23a ratchet connection, said notches or recesses being adapted to selectively cooperate with the pin 23 to permit relative rotary movement between the handle and spindle members and also to hold the handle in fixed position with reference to the spindle D so as to retain the spring F under stored tension as hereinafter described. 5

The razor is used in the ordinary manner with the parts in the condition shown in Figure 1, during which time the spring F may or may not 10 be under appreciable tension but, as will be observed, the handle is interlocked with the spindle D and assembly of razor parts proper by means of the pin and bayonet slot formations 23, 31. At the end of the shaving operation, the razor 15 blade assembly is loosened by unscrewing the nut section of the spindle from the threaded stem 15 partially as shown in Figure 2 but not so as to completely detach the blade, clamp, etc. With the parts partially loosened, the clamp C 20 and blade B may then be turned angularly with reference to the support A and the rib 13 of the clamp withdrawn from its slot in the blade B and also from the slot 12 of the support and the parts adjusted as shown in Figure 2, where 25 both the clamp C and blade B are angularly rotated with reference to the support, the clamp more than the blade. In this condition, the end section of the spindle may then be tightened up so as to hold the assembly taut but, as will be 30 observed, the edge portions of the blade are fully clear of any adjacent surfaces of either the clamp C or support A and, hence, all edge portions, particularly of the blade, are freely accessible to contact with air or rinsing water. Ordinarily, 35 the user will rinse the usual residue of shaving cream or soap under a faucet or in a bowl of water either when the razor is in the condition shown in Figure 1 or as shown in Figure 2 and the razor is then ready for the next or drying 40 operation.

The drying is accomplished as follows: Either before or after the loosening of the blade assembly from the condition shown in Figure 1 to that shown in Figure 2, the user will rotate 45 the handle member E in the direction indicated by the arrow x in Figure 1, relative to the spindle member D, the latter being conveniently gripped by the knurled section 24 and the handle, of course, by the knurled portions thereof. As the 50 handle member is thus rotated, and to which the outer end of the spring is secured as indicated at 33, the inner hooked end 22 of the spring will, if it has not previously been so engaged, enter the slot 21 of the spindle member and 55 consequently be tensioned by the rotation of the handle. During this rotation, the inner end of the handle member will, on account of the sloping edges 34 thereof adjacent the notches 31, slide over the pin 23 but the handle member will 60 be caught by the pin when released so as to prevent unwinding or untensioning of the spring. During this operation of tensioning the spring the user will, of course, exert some force to maintain the handle E in its innermost position relative to the spindle member D. By use of a properly designed spring, experience has shown that the handle member E need be rotated only about one full turn relative to the spindle D in order to set up the necessary tension within the 70 spring.

After the spring has been tensioned as above indicated, and assuming the blade assembly rinsed and ready for drying, the user then, while the handle portion is gripped in his hand, depresses 75

the plunger G conveniently with his thumb. Depression of the plunger G with reference to the handle E, releases the engagement between the pin 23 and the notch 31 with which it has been 5 in engagement, whereupon the stored energy of the spring is immediately released and imparts to the spindle D and assembly of support A, blade B and clamp C an exceedingly rapid rotative movement. The energy so released and converted 10 is sufficient to set up enough momentum in the blade assembly to rotate the latter a relatively large number of revolutions so that, after the first revolution or revolution and a half with reference to the handle member E and spring F 15 which is retained thereby, the spring F will have been relieved of its tension and the momentum imparted to the blade assembly will continue the rotation of the latter and the hooked end 22 of the spring will automatically disengage itself 20 from the slot 21 and continue to ride on the flat end 36 of the bearing section 20, as will be evident. By reason of the extremely rapid rotation imparted to the blade assembly, any loose moisture not only on the blade but on the support 25 and clamp will be thrown off by centrifugal force and the continued rotation in the air will effect a substantial instantaneous drying of all the parts. As will be evident from inspection of Figure 3, 30 not only does the collar 29 of the plunger prevent disassembling of the handle member from the other parts but due to its being disposed within the recess 30, retardation of the rotative movement is prevented since the user's thumb will no longer contact the plunger when it and the 35 spindle and associated parts commence their rapid rotation. After the drying as above described, the handle member may then be pushed down so as to effect engagement of the pin and notch 23—31 and the spring tensioned at that 40 time if desired. The blade assembly is then loosened and the parts restored to their normal condition as shown in Figure 1, thus placing the razor in condition for use. In actual practice, the loosening and positioning of the blade preparatory to the drying operation and the tensioning 45 of the spring and subsequent release may all be effected in a few seconds, thus doing entirely away with the necessity of completely removing the blade and drying it as has heretofore been 50 customary.

As will also be obvious, the same rotative effect may be employed in rinsing the blade assembly where it is found difficult to remove some of the 55 shaving creams by the ordinary rinsing methods. In such cases, the spring would of course be tensioned twice, once for effecting the rinsing operation and again for the drying operation.

Referring to Figure 6, this illustrates another method by which the blade assembly may be conditioned for the operation with the particular type of razor chosen for illustration. As there shown, the clamp and blade are loosened as before but instead of fully disengaging the rib 13 of the clamp from the slot in the blade, it is left 60 partially within the blade and the blade and clamp both angularly adjusted simultaneously and equally with reference to the support A so that the clamping pressure when re-tightened is effected directly between the clamp C and support A, thus leaving the blade B free to float or vibrate between the clamp and support with the same results as previously described.

As will be evident to those skilled in the art, the handle, spindle and plunger may all be readily manufactured very cheaply in quantities and

quickly assembled. The additional cost is comparatively slight and no changes are involved in the essential characteristic features of the blade assembly and use thereof. As further evident, the improvements may be incorporated either in new razors or the handle, spindle, plunger, spring assembly may be substituted for the regular handles of razors now in use.

The construction herein shown and described is what is now considered the preferred embodiment of the invention, particularly as applied to the particular type of razor chosen for illustration. It is obvious, however, that many changes in details of construction and formation of the parts may be made without departing from the spirit of the invention and that the improvements may be incorporated in various other types of safety razors, all without departing from the spirit of the invention. All such changes and modifications are contemplated that come within the scope of the claims appended hereto.

What is claimed is:

1. A combined handle and rotating device for safety razors, comprising a spindle member having means at one end for removable connection to the razor head, said spindle having a bearing portion terminating in an axially extending plunger, a handle member journaled at one end on said bearing portion and journaled at its opposite end on said plunger for limited axial movement relative thereto, spring tension means housed within and secured at one end to one of said members and detachably secured at its other end to the other of said members, and a ratchet connection between said handle member and the bearing portion of said spindle member for releasably securing said spindle and handle members together to permit relative rotary movement therebetween in one direction to place said spring tension means under torsional strain, whereby axial movement of said plunger relative to said handle member releases the spindle from said ratchet connection for free and rapid rotation imparted by the stored energy of said spring tension means.

2. A combined handle and rotating device for safety razors, comprising a spindle having means at one end for removable connection to the razor head, said spindle having a bearing portion provided with a recess and also having an axially extending plunger secured thereto, a handle member journaled at one end on said bearing portion and journaled at its opposite end on said plunger for limited axial movement relative thereto, the free end of said plunger in one position projecting beyond the end of said handle and in another position being housed within said handle, spring tension means housed within and secured to said handle member, the opposite end of said spring tension means being detachably housed in the recess of said bearing portion, and a pin and slot connection for releasably securing said spindle to said handle to permit relative rotary movement therebetween in one direction only to place said spring tension means under torsional strain, and inward pressure on said plunger relative to said handle releases said pin and slot connection and said spring to permit free rotation of said spindle imparted by the stored energy of said spring tension means.

3. A combined handle and rotating device for safety razors, comprising a spindle member having means at one end for removable connection to the razor head, said spindle having a bearing portion and an axially extending plunger, a

- handle member journaled at one end on said bearing portion and journaled at its opposite end on said plunger for limited axial movement relative thereto, spring tension means housed within and secured at one end to one of said members and detachably secured at its other end to the other of said members, said spring tension means surrounding said plunger, and means for releasably securing said spindle to said handle to permit relative rotary movement therebetween in one direction to place said spring tension means under torsional strain, axial movement of said plunger relative to said handle releasing the spindle therefrom for free rotation imparted by the stored energy of said spring tension means, said spring and said spindle being automatically separated from one another after initial rotative impetus has been imparted to said spindle by said spring.
5. A combined handle and rotating device for safety razors, comprising a spindle having means at one end for removable connection to the razor head, said spindle having a bearing portion provided with a recess and also having an axially extending plunger secured thereto, a handle member journaled at one end on said bearing portion and journaled at its opposite end on said plunger for limited axial movement relative thereto, the free end of said plunger in one position projecting beyond the end of said handle and in depressed position being housed within said handle, spring tension means housed within and secured to said handle member, the opposite end of said spring tension means surrounding said plunger and detachably engaged with the recess of said bearing portion, and a pin and slot connection between said spindle and said handle to permit relative rotary movement therebetween in one direction only to place said spring tension means under torsional strain, whereby the inward movement of said plunger relative to said handle disengages said pin and slot connection and releases said spring to permit free rotation of said spindle imparted by the stored energy of said spring tension means, one end of said spring being automatically disengaged from the recess in said bearing portion of the spindle after initial rotative impetus has been imparted to said spindle by said spring.
20. 4. A combined handle and rotating device for safety razors, comprising a spindle having means at one end for removable connection to the razor head, said spindle having a bearing portion and an axially extending plunger, a handle member journaled at one end on said bearing portion and journaled at its opposite end on said plunger for limited axial movement relative thereto, spring tension means housed within and secured to said handle member, said spring tension means surrounding said plunger and detachably secured to said spindle, and ratchet means for releasably securing said spindle to said handle, said ratchet means when engaged permitting relative rotary movement therebetween in one direction only to place said spring tension means under torsional strain, axial movement of said plunger relative to said handle releasing said ratchet means and

the spindle therefrom for free rotation of said spindle imparted by the stored energy of said spring tension means, said spring and said spindle being automatically separated from one another after initial rotative impetus has been 5 imparted to said spindle by said spring.

5. A combined handle and rotating device for safety razors, comprising a spindle having means at one end for removable connection to the razor head, said spindle having a bearing portion provided with a recess and also having an axially extending plunger secured thereto, a handle member journaled at one end on said bearing portion and journaled at its opposite end on said plunger for limited axial movement relative thereto, the 10 free end of said plunger in one position projecting beyond the end of said handle and in depressed position being housed within said handle, spring tension means housed within and secured to said handle member, the opposite end of said spring 15 tension means surrounding said plunger and detachably engaged with the recess of said bearing portion, and a pin and slot connection between said spindle and said handle to permit relative rotary movement therebetween in one direction 20 only to place said spring tension means under torsional strain, whereby the inward movement of said plunger relative to said handle disengages said pin and slot connection and releases said spring to permit free rotation of said spindle 25 imparted by the stored energy of said spring tension means, one end of said spring being automatically disengaged from the recess in said bearing portion of the spindle after initial rotative impetus has been imparted to said spindle 30 by said spring.
